UNITED STATES PATENT OFFICE.

MICHAEL RONAYNE, OF NEW YORK, N. Y.

LIGHT-SHADE.

1,220,562.

Specification of Letters Patent. Patented Mar. 27, 1917.

Application filed October 26, 1916. Serial No. 127,793.

To all whom it may concern:

Be it known that I, MICHAEL RONAYNE, a citizen of the United States, residing in the city, county, and State of New York, 5 have made certain new and useful Improvements in Light-Shades, of which the following is a description, reference being had to the accompanying drawings.

This invention relates to improved construction of shade for inclosing lamps or other source of light. The object is to obtain a shade to produce the effect of tapestry, which presents an equally pleasing appearance whether illuminated by an interior 15 light or not.

A principal feature of my invention consists in having the inclosed body of the shade made of metal sufficiently stiff to provide stability to its form and support a film 20 of decorative coloring matter partly embedded in small perforations in the metal, so the whole device is translucent except for very small portions of the metal between the perforations.

25 In the drawings forming part hereof, Figure 1 is a perspective view of a shade embodying my invention, Fig. 2 is a vertical section on the line $x-x$ and Fig. 3 is a portion of the body broken away to show the 30 method of construction.

In lamp shades a desirable point is to combine pleasing effect with stability. Another desirable characteristic is to have the shade decorative when only subjected to exterior light.

35 My invention utilizes a thin film made up of plastic, translucent, coloring matter, which may be dispensed in the shape of pleasing figures or designs as a surrounding for an 40 inclosed light. As a means for stiffening and holding the decorative film in position, I use a fibrous translucent material A, for a keeper or backing and on this superimpose a thin sheet of metal B, provided with regular 45 distanced openings C, quite close together, so there will be but little metal to obstruct the light. The backing A may be of rice paper, or other similar translucent material, which is first joined to the metal 50 by a layer of silicate of soda. The side of the backing A, which forms the inner side of the shade, is then covered with a thin coat of shellac.

55 The body of the shade is then ready to receive the decorative film F, which is placed in position on the metal. This may be in

the form of decorative colors of a design on the outer face of the metal.

The film F, is of such consistency as to flow readily when being deposited with the 30 air brush but must not be so thin as to run when deposited. Preferably it is composed of a mixture of linseed oil to which is added a little drier and various coloring matter so as to display the figures on the shade. The 35 flat portion of the film on the outer surface of the shade and the thickened portions which lie in the perforations, harden as the coloring matter dries. The thicker portions of the film in the perforations which fasten 40 or tie the flat portions of the film to the metal, also act so as to refract the light passing through the shade when it is illuminated on the interior and thereby enhance the effect, presenting to the eye of the beholder 45 something like figured tapestry.

It will be understood that the film of coloring matter when deposited is prevented from passing through the shade by the translucent backing, which may be white, or 50 of any desired body color, softening in effect on the light. The film is applied by means of an air brush and stencils, the colors being blown on the face of the metal, portions thereof being intimately and evenly 55 deposited in the perforations, which will be thicker than the rest, but the whole film is joined up with them in the completion of the figures or design.

By using the prepared backing A I am 60 enabled to deposit and hold the film of colors in position and the light passing through their increased thickness at the perforations, shows up the design when light is used on the interior of the shade in a pleasing manner. But the film carrying the design of colors is continuous on the face of the metal 65 so that when the light strikes the shade from the outside, any design thereon is still 70 presented to the eye as a completed picture. 75

It will be understood that the perforations in the metal are so close to each other that there is but little intervening metal, and the size of the holes in the metal are of such dimensions that they will retain, without 80 danger of loosening, the thickened portions 85 of the film contained therein. I have found in practice that the holes in the metal should be about one-twentieth of an inch in diameter, or about fifteen to the inch, including 90 the metal between.

The shade may be made in various shapes

and many styles of coloring or designs may be employed. In the style of shade shown in the drawing, I preferably employ a retaining ring D at the base and another E at 5 the top to which cross bars G are fastened for securing the shade in position, but other means may be employed for these purposes.

What I claim as my invention is:

- 10 1. A lamp shade for inclosing a source of light, comprising an outer film of plastic ornamental coloring matter supported in position on a perforated metal body and a translucent inner lining portion secured thereto, substantially as shown and described.
- 15 2. In a lamp shade for surrounding a source of light a perforated metal body having on its interior side a translucent lining extending over the perforations in the metal

and an outer inclosing continuous translucent film supported by the metal body, substantially as and for the purpose shown and described. 20

3. A lamp shade for surrounding a source of light comprising a plastic film of translucent coloring matter supported on a body 25 of perforated metal and an interior translucent lining secured to the metal body combined with suitable means for securing the same to a lamp or other source of light, substantially as and for the purpose shown and 30 described.

MICHAEL RONAYNE.
